UNITED STATES PATENT OFFICE

HARRY W. PROTZELLER, OF EAST CHICAGO, INDIANA, ASSIGNOR TO O. F. JORDAN COMPANY, OF EAST CHICAGO, INDIANA, A CORPORATION OF INDIANA

EXCAVATOR CAR

Application filed March 7, 1929. Serial No. 345,166.

This invention relates to improvements in excavator cars and it consists of the matters hereinafter described and more particularly pointed out in the appended claims.

10 Railway maintenance work often requires the digging up of ballast and road bed material along the track at different distances laterally from the track within certain limits. Such work sometimes calls for trenching of different depths along the track for drainage purpose and sometimes it is desired to remove, clean and replace ballast to keep the road bed in a good condition.

The primary object of the invention is to 15 provide a car or vehicle movable upon a railroad track whereby such operations may be advantageously carried on economically and faster than it is now possible with hand labor.

20 Another object of the invention is to provide a car or vehicle including an excavating or digging mechanism, which is normally carried in transport at one side of the car so as not to interfere with traffic conditions and 25 which may be easily set and held in position for operation at different distances from the track upon which the car is travelling.

A further object of the invention is to provide a simple and efficient supporting means 30 for the excavating element, which may be readily actuated to properly locate and hold the excavating element in the desired operative position.

35 Still another object of the invention is to provide automatic means which will insure the perpendicularity of the excavating element as when the car is making a curve, irrespective of the fact of whether the element 40 is operating upon the high or low side of the track.

These objects of the invention as well as others, together with the many advantages thereof will more fully appear as I proceed 45 with my specification.

In the drawings:

Fig. 1 is a view in side elevation of an excavator car embodying one form of my invention.

50 Fig. 2 is a top plan view thereof with the

roof or canopy removed to better illustrate the several parts.

Fig. 3 is a transverse vertical sectional view through the car on an enlarged scale as taken on the line 3—3 of Fig. 2.

Fig. 4 is a vertical detail sectional view on a further enlarged scale as taken on the line 4—4 of Fig. 3.

Fig. 5 is a vertical sectional view through a part of the car as taken on the line 5—5 of Fig. 3.

Fig. 6 is a horizontal detail vertical sectional view as taken on the line 6—6 of Fig. 3.

In general my improved construction embodies a vehicle on the order of a railroad 65 car of that type commonly termed a "flat car". At one side thereof is provided a digging or excavating mechanism so mounted upon supporting members on the car that

said mechanism may be positioned at different distances laterally from the car and may be adjusted to excavate to the desired depth. When the car is to be transported from one place of use to another, the excavating mechanism may be swung upwardly out of operative excavating position and may then be swung inwardly toward the car so as to be out of the way, thus providing the necessary clearance space for passing trains. When the car is in operation upon a curve, it is evident that one side of the car will be higher than the other at which time certain means operates automatically to maintain the excavating mechanism in a perpendicular position, no matter whether said mechanism happens to be on the inside or outside of the curve. Thus in trenching operations, it is apparent that the trench being made and especially when the same is a relatively deep one, will have side walls of such perpendicularity as to prevent caving in of either side wall due to overhang.

Referring now in detail to that embodiment of the invention, illustrated in the accompanying drawings, 1 indicates as a whole a vehicle in the form of a railroad car similar to a "flat car" and which car is adapted for travel upon the rails of a railroad track 2. Said car includes the usual under framing 3 and deck 4, mounted on front and rear 100

wheeled trucks 5—5, the term "front" and "rear" merely being used relatively and for convenience and in accordance with the direction in which the car moves upon the track when in actual use.

- 5 At one side of the car between its ends, the underframing and decking are so formed as to provide a substantially long but rather shallow recess or cut-in side 6. Disposed 10 along opposite sides of the car in the desired longitudinally spaced relation, are upright posts or standards 7 and 8 respectively, upon which a suitable roof or canopy 4^a is supported the desired distance above the deck 4. 15 On the median line of the car at a suitable distance from the front end thereof, are located front and rear upright masts 9 and 10 respectively, each of which includes a substantially horizontally disposed boom 11. As 20 each mast and boom are substantially alike, a detailed description of one will suffice for both.

Each mast is made up of an I beam 12 and secured to each flange thereof is a substantially kite shaped gusset plate 13. The bottom ends of said beam and gusset plates are fixed to a foot plate 14 including a hemispherical bearing member 15 which seats in a correspondingly shaped socket 16 in a bearing plate 17. This bearing plate rests upon the deck 4 on the median line of the car and is secured to said deck and to the center sills of the framing 3. On the top end of the mast is secured a cap 18 with an axially disposed upright stud 19 that bears in a recess 20 formed in a worm gear segment 21 of substantially large radius and which extends transversely of the car.

The worm gear segment has lateral guide shoulders 22—22 that engage with similar guide shoulders 23—23 on the inner surfaces of a transversely extending housing 24. Said housing is dependingly supported from side and intermediate stringers 25 and 26 respectively, forming a part of the supporting structure for the roof or canopy 4^a. Both housings 24—24 are connected together by angle bars 24^a as best shown in Fig. 4.

In each housing 24 there is journalled at its ends a horizontally disposed shaft 27 having a worm 28 between its ends which meshes with the worm gear segment 21. On one end of each shaft, beyond the associated end of the housing 24, is secured a worm gear 29, and both gears 29 mesh with worms 30—30 fixed on a longitudinally extending horizontally disposed shaft 31 that is journalled at its ends in the associated ends of the housings 24—24 as best shown in Fig. 5. This shaft 30 is operatively driven from a reversible electric motor 32 supported from one of the posts 8 at that side of the car opposite the cut-in or recessed side thereof.

Each boom 11 comprises a pair of channel bars 33 secured to the gusset plates 13 so as

to form a long arm 33^a and a short arm 33^b therefor, said boom and gusset plates being suitably braced as at 34 in Fig. 3. Near the outer end of the long arm of each boom, between the channels 33 thereof is secured a 70 spacing block 35 that includes a depending stud 36 best shown in Fig. 3. Pivoted on each stud 36 is a bracket 37, and the brackets of both booms are connected together by a pair of channels 38—38. Thus the brackets 75 37 and the channels 38 constitute an elongated rectangular excavating mechanism supporting frame that is pivotally connected to each boom to provide, in connection with the upright posts or masts, a parallelogram 80 arrangement. When the masts are swung about their end bearings, the excavating mechanism supporting frame may be swung from a position wherein it is disposed above the cut-in side of the car to one spaced laterally therefrom as best shown in dotted and full lines in Fig. 2.

To the forward end of said excavating element frame is pivotally mounted one end of an excavating or digging mechanism indicated as a whole by the numeral 39 in Fig. 1. This excavating or digging mechanism which is of the chain and bucket type comprises a frame 40 pivoted at one end to a short horizontally disposed shaft 41 journalled in downwardly and forwardly extending brackets 42 on the front end of said frame. At the other end of said frame is journalled a shaft 43 and on said shafts 41 and 43 are sprockets 44 only one of which is shown in Fig. 1. Trained about said sprockets 44 are chains 45 carrying buckets 46, those portions of the chains between the sprockets 44 engaging rollers 47 on said frame. On that end of the shaft 41 outwardly beyond the frame 40 is secured a sprocket 48 driven by a chain 49 from a suitable speed reduction set 50 carried by the outer channel 38. This set 50 is in turn driven by an electric motor 51 also mounted on said last mentioned channel 38.

As is apparent from Fig. 1, when the motor 51 is running, the sprocket 48 is driven counter clock-wise and the buckets 46 will work against the breast 52 of a trench to remove material therefrom. This excavated material is discharged from the buckets as they approach the sprocket 48 into the usual belt conveyors which have been omitted for the sake of clearness, such conveyors being of any well-known kind.

Means is provided for raising and lowering the excavating mechanism out of and into operative position and such means is as follows: On the rear end of the frame provided by the channels 38—38 is mounted a reversible electric motor 53 which drives a transverse shaft 54, journalled in suitable bearings on and near the rear ends of said channels, through suitable speed reducing 125

means 55. On each end of said shaft is fixed a drum 56 and upon said drum is wound and unwound one end of a pair of cables 57, the other end of which is connected as at 58 to each side of the frame 40. Thus, when the motor 53 is running in one direction the pulleys 56 will wind up the cable which will raise the free end of the frame toward and into substantially parallel relation with the channels 38 into the inoperative position and when said motor is running in the other direction, the free end is lowered into the desired operative position. In this respect it is pointed out that the speed reducing gear 55 is of the worm gear type so that it acts to support the excavating mechanism in any desired position so that it may operate at any desired depth.

To swing the booms laterally away from and toward the car I provide the following. On one of the posts 8 at one side of the car and preferably on that post, to the rear of the rearmost mast 10 I mount a reversible electric motor 59 by means of brackets 60. Also fixed to said post are brackets 61-61 in which is journaled a shaft 62. On said shaft between the brackets 61-61 is fixed a drum 63 and on the shaft 62 below the drum is a worm gear 64 driven by a worm 65 on the armature shaft of the motor 59. A cable 66 is wound about the drum 63 and one end is attached to the short arm 33^b of the boom while the other end of said cable is attached to the long arm of the boom.

When the motor 59 is running in one direction the drum 63 is rotated to wind up on one end of the cable and pay out on the other end whereby the booms are swung outwardly to the position desired for the channels 38. In Fig. 2 I have shown said channels as in the limit of their outward movement so as to locate the excavator element as far as possible from the car. When said motor is running in the opposite direction, the booms 11 are swung in the other direction to pull the channels 38 in toward the car so that they will be located in the plane of the cut-in sides of the car as best shown in dotted lines in Fig. 2.

Means are provided for holding the booms in the desired position and such means are best illustrated in Figs. 1 and 2. On another one of the posts 8 is rotatively secured a collar 67 to which one end of a telescopic brace 68 is operatively connected, the other end of said brace being operatively connected to the long arm 33^a of the rearmost boom. Said brace comprises telescopic inner and outer tubes 68^a and 68^b respectively, and the inner end of the inner tube is pivotally connected to the collar 67 as at 69. The outer end of the outer tube 68^b is connected by a ball and socket joint 70 to the rear side of the long arm of the rearmost boom. 71 indicates as a whole a hydraulic locking means located on the outer end of said inner tube

and through which the inner end of the outer tube telescopes into the associated end of the inner tube. This means 71 is connected up as by a conduit 72 with a source of fluid under pressure as in the tank 73.

When pressure is shut off from the means 71 the tube 68^b is free to telescope (in or out) with respect to the tube 68^a so that the booms may be swung into the desired position. When said position has been reached, fluid under pressure is admitted to the means 71 which clamps upon the tube 68^b to rigidly secure it to the tube 68^a, thereby providing a brace adjustable in length to hold the booms in any desired relation with respect to the car.

It is desirable to maintain the excavating mechanism in a perpendicular plane at all times irrespective of the angular inclination the deck of the car may assume from the horizontal as for instance when the car is on a curve wherein the outer rail is higher than the inner rail. To maintain said perpendicularity I provide a compensating means best shown in Fig. 3. On one of the gusset plates 13 of the mast 9 I pivot as at 74, the top end of a swingable pendulum that pendants vertically. On each side of the bottom end of said pendulum are contacts 76 and 77, respectively, and above said contacts is a weight 78. This pendulum is grounded to the car as indicated by the line 79. To the gusset plate 13 and spaced a short distance to each side of the bottom end of the pendulum are contacts 76^a and 77^a respectively, connected by conductors 80 and 81 respectively with the motor 32.

In Fig. 3 I have illustrated the car as taking a curve with the higher rail at the left hand side of the track. As the car approaches said curve, the left hand side thereof as viewed in said Fig. 3 will be elevated slightly, bringing the contact 77 into engagement with the contact 77^a closing the circuit to one side of the motor so that it drives the shafts 27 in the proper direction. When said shafts 27 are driven in the proper direction the worms 28 will impart an endwise movement to the segmental worm gears 21 to rock the masts and booms about the bottom ends of the booms until the masts assume a perpendicular position wherein the contact 77^a will move away from the contact 77. This stops the motor 32 with the masts in perpendicular position so that the plane of the position of the excavating mechanism when in actual operation remains unchanged. When the car approaches straight track again the contact 76^a will move toward the contact 76 and through the conductor 80 will cause the motor 32 to run in the opposite direction to swing the top end of the masts in the other direction until it stands perpendicular to the deck of the car which is now in a horizontal position. So soon as this condition is

reached, the contacts 76—76^a are separated and the motor 32 stops.

From the above it is apparent that the mechanism just described compensates for the inclination of the car to the horizontal to always maintain the masts in perpendicular position and the excavating mechanism in its proper position with respect thereto. This feature is important because the sides 10 of the trench or ditch being dug are always maintained at that perpendicularity resisting caving in even when the car is working upon a curve.

In the rocking movement of the masts to 15 retain their perpendicularity, it is apparent that the long arm 33^a of each boom forms quite a load and which load would be imposed on the motor when the mast is rocked to the right as in Fig. 3, if it were not for 20 means now to be described. To offset said load, I support upon the short arm 33^b of each boom a weight 33^c which substantially counterbalances the long arms of the booms.

On the rear end of the deck of the car I 25 mount a gasoline engine 83 for driving a generator 84 from which power or current for the various motors mentioned is supplied. To move the car along the track, at a speed 30 commensurate with the excavating being carried out, I provide under the deck at the forward end of a car, a motor driven winch 35 85 upon which is wound one end of a cable 86, the other end of which is anchored to the track at a suitable distance in advance of the car. When it is desired to move the car forward, the winch is operated to wind up that amount of cable necessary to move the car along to maintain the excavating mechanism up against the trench breast 52.

40 The construction above described has many advantages. By means thereof, the supporting masts for the excavating mechanism may be actuated to locate said mechanism in any one of a number of positions laterally from the car and in which position said mechanism is held and operated for its intended purpose. The construction described may be used for many purposes such as removing ballast for cleaning the same or for forming 45 drainage ditches of various depths for either ballast or sub-grade drainage.

50 The excavating mechanism may be quickly swung into and out of operative position to allow passage of trains on adjacent tracks and when said mechanism is swung in toward the car for transport purpose, that amount of clearance recognized as standard between 55 passing cars on adjacent tracks is maintained.

Another feature exists in the fact that the 60 excavating mechanism may be always maintained to operate in a perpendicular plane irrespective of the angular inclination of the car as when passing about a curve.

65 While in describing the invention, I have referred in detail to the form, arrangement

and construction of the several parts thereof the same is to be considered as merely illustrative thereof so that I do not wish to be limited thereto except as may be pointed out in the appended claims.

I claim as my invention:

1. In combination with a vehicle, excavating mechanism at one side thereof, supporting means on said vehicle capable of a lateral horizontal swinging movement toward and away from the vehicle about at least two axes and to one end of which said excavating mechanism is operatively connected at points spaced in one direction from said axes, said supporting means being swingable about said axes to move said end into different positions laterally from said side of said vehicle and means on the other end of said supporting means beyond said axes in the other direction to counterbalance said excavating mechanism.

2. In combination with a vehicle, a pair of supporting members mounted for a horizontal swinging movement about spaced axes whereby one end of said members may be moved into different positions laterally with respect to the side of the vehicle, a frame pivotably carried by said ends of said members and excavating mechanism pivotally connected to said frame for a raising and lowering movement.

3. In combination with a vehicle, means providing parallel booms pivoted adjacent one end with respect to the vehicle whereby the other end of said booms may be swung into different positions laterally of the vehicle, a frame member pivotally carried by said last mentioned end of said booms to provide a parallelogram arrangement and excavating mechanism carried by said frame.

4. In combination with a vehicle, means providing parallel booms pivoted adjacent one end with respect to the vehicle whereby the other end of said booms may be swung into different positions laterally of the vehicle, a frame member carried by said last mentioned end of said booms, and excavating mechanism carried by said frame member and capable of a vertical adjustment with respect thereto.

5. In combination with a vehicle, means providing parallel booms pivoted adjacent one end with respect to the vehicle whereby the other end of said booms may be swung into different positions laterally of the vehicle, a frame member carried by said last mentioned end of said booms, excavating mechanism carried by said frame member, and means on the first mentioned end of the booms for counterbalancing said frame and excavating mechanism.

6. In combination with a vehicle, a substantially vertical mast, means providing top and bottom bearings on said vehicle for said mast about which it may be turned the top bearing member being laterally movable about the bottom one as an axis, a boom fixed to said

mast and an excavating mechanism positioned adjacent one end of the boom and movable toward and away from the vehicle in the turning movement of the mast.

5 7. In combination with a vehicle, an excavating mechanism, a supporting frame therefor disposed longitudinally of the vehicle, and means connecting said frame and vehicle for a horizontal swinging parallelogram movement away from and toward the vehicle to locate said frame and mechanism in any one of a number of different operative positions spaced laterally from the vehicle.

10 8. In combination with a vehicle, an excavating mechanism, a supporting frame therefor normally disposed longitudinally along and within the plane of one side of the vehicle, means connecting said vehicle and frame for a horizontal swinging parallelogram movement of the latter outwardly away from the vehicle to position said excavating mechanism with respect to the vehicle and means carried by said frame for driving the excavating mechanism.

15 9. In combination with a vehicle, an excavating mechanism, a supporting frame therefor disposed longitudinally of the vehicle, means connecting said frame and vehicle for a horizontal swinging parallelogram movement away from and toward the vehicle to locate said frame and mechanism in any one of a number of different operative positions spaced laterally from the vehicle and means operative from the vehicle for holding the frame against undesired horizontal swinging movement after said mechanism has been located in an operative position.

20 10. In combination with a vehicle, an excavating mechanism, a supporting frame therefor disposed longitudinally of the vehicle, means connecting said frame and vehicle for a horizontal swinging parallelogram movement away from and toward the vehicle to locate said frame and mechanism in any one of a number of different operative positions spaced laterally from the vehicle and means for raising and lowering said mechanism with respect to said frame, out of and into excavating position.

25 11. In combination with a vehicle, an excavating mechanism, a supporting frame therefor disposed longitudinally of the vehicle, means connecting said frame and vehicle for a horizontal swinging parallelogram movement away from and toward the vehicle to locate said frame and mechanism in any one of a number of different operative positions spaced laterally from the vehicle and means for raising and lowering said mechanisms with respect to said frame, out of and into excavating position, said last mentioned means being operable to determine the effective depth of the excavation to be made.

30 12. In combination with a vehicle, a pair

of horizontally swingable booms pivoted at one end to the vehicle, a frame connecting the other end of said booms and coacting therewith to provide a parallelogram arrangement and which frame is movably laterally away from and toward the vehicle into and out of operative position in the swinging of said booms and an excavating mechanism of the endless conveyor type carried by said frame.

35 13. In combination with a vehicle, a pair of horizontal swingable booms pivoted at one end to the vehicle, a frame connecting the other end of said booms and coacting therewith to provide a parallelogram arrangement and which frame is movable laterally away from and toward the vehicle into and out of operative position in the swinging of said booms, and excavating mechanism of the endless conveyor type pivoted at one end to said frame and means for raising and lowering the other end of said mechanism to determine the effective depth of the excavation to be made or to bring said mechanism into an inoperative position.

40 In testimony whereof, I have hereunto set my hand, this 1st day of March, 1929.

HARRY W. PROTZELLER.
